UNITED STATES PATENT OFFICE.

KNUTE STORAKER, OF WESTCHESTER, NEW YORK.

SCRIBER'S COMPASS.

1,111,192.

Specification of Letters Patent.

Patented Sept. 22, 1914.

Application filed December 18, 1913. Serial No. 807,395.

To all whom it may concern:

Be it known that I, KNUTE STORAKER, a subject of the King of Norway, (having declared his intention of becoming a citizen of the United States,) and a resident of Westchester, county of Bronx, and State of New York, have invented certain new and useful Improvements in Scribers' Compasses, of which the following is a specification.

10 My invention relates to the special class of compasses used mainly by builders, carpenters and other artisans for the purpose of laying out and marking work to be done, and my main object is to adapt the device to the use of pencils and points of any length,—the invention consisting in the specific construction described and claimed herein.

In the accompanying drawings, Figures 1 and 2 represent elevations of the opposite sides of my improved scribing compass with a long marking pencil in position; Fig. 3, front elevation, with the pencil broken away in part.

The legs *a*, and *b*, of the compass are pivotally connected at *c*, in the usual way, and are held apart more or less as required for use by means of the segmental arm *d*, attached to the leg *a*, in conjunction with a clamp *e*, upon the other leg *b*. The segmental arm and clamp are old in this connection but the segmental arm has heretofore passed through a central longitudinal slot in one leg, protruding in alinement therewith, which is expressly what my invention is designed to avoid. Hence I form and secure my segmental arm *d*, in such manner that it extends across one side of the leg *b*, and through a loop *e'*, on a screw *e*, the shank of which extends through a hole in the leg *b*, and into engagement with a set nut *c*, bearing against the opposite side of the leg, and by means of which the legs may be held in prescribed relation to one another. That is to say the tightening of the nut *c*, binds the segmental arm *d*, tightly against the side of the leg *b*, through the medium of the screw *e*. By this construction the outer or front side of the leg *b*, is left free and unobstructed so that the whole length thereof is available for the accommodation of a full length of marking pencil *p*.

The lower end of the leg *b*, is formed with

a threaded split tube *b'*, for the reception 55 and retention of the lower portion of the marking pencil *p*,—the sides of the tube being tightened against the pencil *p*, by means of a sleeve nut *b*,—the longitudinal slots *b*, in the tube *b'*, which is slightly 60 conical, admitting of the insertion of the pencil when the sleeve nut *b*, is loosened up.

The pencil tube *b'*, is arranged on the outer or front side of the leg *b*, and in parallelism therewith, so that a new or full sized 65 pencil *p*, may be positioned to extend for the greater portion of the length of the leg and beyond the clamp *e*.

A steel point may obviously be substituted in lieu of the pencil if so desired to be used 70 for marking purposes &c.

By my construction and arrangement of parts I am enabled to utilize pencils or portions thereof of any length.

What I claim as my invention and desire 75 to secure by Letters Patent is,

1. In a scribe's compass of the character designated, a segmental arm attached to one leg and extending laterally across one side of the other leg, a loop-screw engaging said 80 segmental arm and extending through said other leg, a nut engaging said loop screw and bearing against said other leg, the latter formed with a slit pencil tube on its outer side, and a nut sleeve engaging with said pencil tube, whereby a pencil may be used of a length sufficient to extend beyond the segmental clamping device as and for the purpose set forth.

2. A scribe's compass of the character 90 designated comprising pivotally connected legs, a segmental arm attached to one leg and extending across a side of the other leg, clamping means on the latter for engaging with said segmental arm, said other leg 95 being also formed with a slit pencil tube in parallelism with its outer side, and a sleeve nut engaging said pencil tube, whereby a pencil may be used of a length sufficient to extend beyond the segmental clamping device as and for the purpose set forth. 100

KNUTE STORAKER.
